OPEN PLATE FLOOR

Ernest M. Wichert, Mount Lebanon Township,
Allegheny County, Pa.

Application February 23, 1951, Serial No. 212,331

5 Claims. (Cl. 14—73)

1

This invention relates to heavy duty light weight metal floors and particularly to floors of a sort suitable for incorporation in bridges.

More particularly referring to the heavy duty light weight floor of my invention these floors belong to a type known as open floors in contradistinction particularly to floors comprising a metal framework, lattice or cellular metal structure covered or filled with concrete or other roadway material, which latter type are to be considered as solid floors.

Heavy duty open floors for use in bridges and like construction possess many physical advantages over the more conventional heavy duty solid floors. They present properties of increased endurance as compared to solid floors in which the filling material tends to relatively rapid deterioration by weathering and abrasion. Also open heavy duty floors provide better traction surfaces than solid floors and have the very important advantage of economy in the time and cost involved in the construction of the floor. Conventional open heavy duty floors have, however, presented the disadvantage that they are not economical.

A primary object of this invention is to provide a light weight heavy duty floor which can be produced more economically in the weight and/or quality of steel used per unit of surface area than is possible with open heavy duty floors of the sorts previously made.

Another object of my invention is to provide an open heavy duty floor capable of such integration in a composite structure with the supporting members of a bridge or the like that saving in the weight of those supporting members is effected.

Another object of my invention is to provide a flooring panel including my flooring plate which allows great savings in fabrication, transportation and installation; as for example by including flooring beams which are standard rolled beams requiring no fabricating whatever so that they can be delivered in their final form from the rolling mill nearest the site of their installation and can be erected and integrated in the flooring structure in the form in which they arrive at that site.

I attain the above noted and other advantages in a heavy duty open metal floor by taking full advantage of physical principles; viz. that instantaneously applied loads produce dynamic stresses which are measured by the laws governing the energy of bodies in motion and that the effect of these dynamic stresses vary greatly depending on the mass of the supporting structure. There-

2

fore, I so design my floor structure that it effectively and reliably counteracts applied loads by composite and continuous action in all directions within an entire bridge panel.

5 This is in contradistinction to conventional light weight open floors in which only comparatively small and light sections of the flooring can be relied upon to counteract a concentrated application of forces. By effectively and reliably 10 integrating the flooring proper with the floor supporting system I succeed in greatly reducing deflections of the various members of the entire bridge supporting structure, thereby greatly increasing the rigidity and strength of that structure. 15 This result has been proven by various tests made on a full size model bridge designed in accordance with standard A. A. S. H. O. specifications.

As shown in the accompanying drawings, my 20 monogenetic trussed open plate floor consists primarily of a plurality of plates with transverse trusses, said trusses being part of the original steel plate and having portions spaced in approximate parallelism with each other in the floor 25 structure and extended downwardly substantially at a right angle to the road surface. Desirably such trussed construction is provided by punching, cutting and bending downwardly bent portions of the trusses conforming generally to a spaced irregular pattern of the open flooring surface.

In the accompanying drawings, exemplary of the embodiment of my invention:

Fig. I is a broken plan view of my monogenetic 30 flooring plate showing the plate integrated with flooring beams and stress-distributing bars in an open flooring panel.

Fig. II is a vertical sectional view taken in the plane of the section line II—II of Fig. I, showing 35 a downwardly-extended truss portion and illustrating in broken lines the mounting of the flooring beams of a panel on underlying supporting beams.

Fig. III is a vertical sectional view taken in the plane of the section line III—III of Fig. I, showing 40 one of the stress-distributing bars with which the monogenetic trussed plate of Fig. I is equipped.

Fig. IV is a vertical sectional view taken in the plane of the section line IV—IV of Fig. I, showing 45 several of the trussed components of my monogenetic floor with stress-distributing bars integrated therewith.

Fig. V is a vertical sectional view taken in the 50 plane of the section line V—V of Fig. I, showing

the same components as shown in Fig. IV but in the form and arrangement determined by the different plane in which the view is taken.

Fig. VI is a view in vertical section and on an enlarged scale illustrating the welding of a vertical stress-distributing bar to horizontal components of the trussed flooring plate.

Fig. VII is a detail view in vertical section and an enlarged scale illustrating the welding of the flooring plate to one of the flooring beams.

Fig. VIII is a horizontal sectional view taken in the plane of the section line VIII—VIII of Fig. II, illustrating the welding of the flooring beams of the floor assembly to underlying supporting beams.

Fig. IX is a broken plan view of one side of a roadway composed of open flooring panels in accordance with the preceding figures of the drawings.

Fig. X is a broken plan view of my monogenetic flooring plate, showing the plate without stress-distributing bars but provided with a battendeck covering.

Fig. XI is a broken plan view of one of my flooring plates, illustrating steps in a preferred method of manufacture.

The flooring plate of my invention as produced and from its inception is a one-piece structure and as such is aptly described by the term "monogenetic." The flooring plate is "open" in that it is provided with a plurality of holes or open spaces which are not intended in the assembly of the plate to be filled with concrete or other filling material. Also the flooring plate has regions extended-downwardly to form an effective truss. Such truss reaches the approximate distance between two opposed margins of the plate, so that in its simple form the plate is composed of horizontal traffic-contacting components and downwardly-extended components. Since the plate is of one piece throughout its extent, it is thus a "trussed" plate and this trussed construction serves greatly to increase the various sections moduli of the plate and the moments of inertia about the composite neutral axes when the flooring plate is integrated in a flooring panel. It is preferable so to construct the flooring plate that it comprises a relatively great number of the trusses each consisting of a plurality of horizontal components and a downwardly-extended component.

I use the terms "horizontal" and "downwardly-extended" and similar terms as terms of broad definition and not as terms of limitation. They comprehend the direction or general plane of the flooring plate components, even though the flooring or a portion thereof may be somewhat inclined to the precise horizontal. A bridge floor may be somewhat inclined because it is on a grade or banked or on a vertical curve etc. Also the bridge may be crowned, in which case a line extending across the flooring may be precisely horizontal at the crown but inclined at the approaches of the bridge.

Referring to the drawings and initially to Figs. I to V inclusive of the drawings more particularly, the monogenetic flooring plate is shown as a continuous structure having a traffic-contacting surface provided by a plurality of horizontal traffic-contacting components 1, 1a and 2 and a plurality of downwardly-extended components 3, to give the trussed construction reference to which has been made. The traffic-contacting components are of angular or irregular contour and thus conform to good practice in giving good trac-

tion and skid-resistance to the tires of vehicles passing over an open flooring comprising the flooring plates. Assuming the preferred method of manufacturing my flooring plate which will be described, the horizontal traffic-contacting components of the flooring plate conform in contour and area to major openings in the general horizontal surface of the plate and in its downwardly-extended components. Thus there is a continuous opening 4 which extends approximately the distance between opposed margins 5 of the plate and which is identical in outline with a downwardly-extended component 3. This extended opening 4 also defines the contour of horizontal components 1 and 1a. The horizontal components 2 conform in contour to holes 6 in the downwardly-extended components 3 of the trussed structure. In addition to openings 4 in the included horizontal area of the plate, the weight of the structure 20 as a whole is reduced and the skid-retardant property of its traffic-contacting surface is improved by variably arranged holes 7 and 8 in horizontal components 1a and 1. Smaller holes 9 in the marginal regions 5 of the plate provide for 25 integration of the plate in a flooring panel and there are other relatively small holes 10 adjacent the junction of the horizontally and downwardly-extended components of the plate structure. These latter holes shown in the drawings provide 30 relief for a deflecting flow of metal during manufacture of the flooring plate when the flooring plate is made in accordance with preferred methods. Whereas the metal of openings 4 and 6 is retained in the trussed construction of the plate, 35 the metal of holes 1, 8, 9, 10 is deleted from the structure of the plate.

Considering now specifically the form and arrangement of the downwardly-extended components 3 of the trussed plate, those components 40 extend in an approximately right angular relation to the horizontal traffic-contacting surface of the plate. As shown particularly in Fig. II of the drawings, these components reach through the approximate distance between two opposed margins of the plate with which margins they have a generally right angular relation. Each downwardly-extended component is a unitary body which is continuous throughout its length. The holes 6 in the body of each of the downwardly-50 extended components 3 are shown as of the form of the horizontal traffic-contacting components 2 and between and laterally beyond these holes that body has its monogenetic continuity with the horizontal structure of the plate.

It has been noted above that a primary object of the invention is to provide a flooring plate, as such and when integrated in a flooring panel, which presents at all points adequate reactance to applied loads. Assuming that the plate is, as 60 shown, a multi-truss flooring plate in which the downwardly-extended components represent an area of metal subtracted from the horizontal traffic-contacting structure of the flooring plate, it is desirable that the plate be provided with added 65 means which supplement the stress-distributing function of the trusses. In Figs. I, III, IV, V and IX of the drawings such means are shown as stress-distributing bars 11 integrated with the horizontal components of the flooring plate.

In the drawings stress-distributing bars 11 are shown as of the same gauge as the metal of which the monogenetic flooring plate itself is composed and the bars are of a depth appropriate to the maximum loading the plate is purposed 70 to sustain. Stress-distributing bars 11 extend

between and past horizontal traffic-contacting components **1** and **2** to which they are welded and extended beneath the furthest separated traffic-contacting components **1a** to which also the bars are welded. The welding to the horizontal components **1a** is shown in Fig. I as a fillet weld **12** and welding to the horizontal components **1** and **2** is indicated also by reference numeral **13** in that figure of the drawings. This latter welding is shown more clearly in Figs. IV and V and on an enlarged scale in Fig. VI which shows a region defined by the broken-line boxing "A" of Fig. V. As shown, the terminals of staggered horizontal components **1** and **2** are downturned at **1b** and **2b** respectively and a stress-distributing bar extends between them with the upper edges of downturned terminals **1b** and **2b** in contact with the opposite surfaces of the bar. The triangular spaces thus formed are filled with welding metal at **13** to give a secure integration of each bar with the horizontal structure of the flooring plate. Desirably the upper edges **14** of the stress-distributing bars are serrated, contributing to the skid-resistant property of the flooring plate.

Because the area of openings **4** and the area of downwardly-extended components **3** are mutually dependent and it is important that these structural components be of a length and depth adequate to impart to the monogenetic structure of the plate the desired trussed effect, the openings **4** in the dimensions of a heavy duty flooring are of greater continuous extent than is desirable for the feet of humans, horses, dogs or for vehicles having wheels of particularly small diameter. The stress-distributing bars thus perform a valuable secondary function by interrupting the continuous extent of the openings.

Attention being directed particularly to Figs. IV and V of the drawings which show the arrangement of trusses and stress-distributing bars in vertical section, it will be seen wherein the flooring plate of my invention is capable of distributing and sustaining applied loads of given value with a minimum weight of the flooring plate and its immediately associated elements and with minimized cost of the steel of which the flooring plate and its associated elements are made. This being more strikingly apparent when the flooring plate and its integrated stress-distributing bars are in turn integrated with immediate supporting structure in a flooring panel, the integration of the plate with the flooring beams will be considered. These flooring beams **15** have one flange of each underlying a marginal region **5** of the flooring plate. Integration between the flooring plate and flooring beams is effected by plug welding through holes **9** adjacent the margins of the plate. Two of the plug welds **16** are shown in Fig. I and in detail in Fig. VII of the drawings and one of the holes **9** for welding to the flange of a flooring beam is provided for each truss of the multi-truss plate. Fig. VII includes the region defined by the broken-line boxing "B" of Fig. II. It will be noted, however, that the section line II-II of Fig. I on which Fig. II is taken is not in the plane of a weld. The plug weld **16** of Fig. VII thus corresponds to a weld fitting one of the holes **9** elsewhere in the showing of Fig. I. Fig. VII also indicates in broken-lines the position of a marginal region of a next adjacent flooring plate on a flange of the same flooring beam.

As an incident of the assembly of the flooring plate and its integrated stress-distributing bars

with the flooring beams, the lateral edges of the downwardly-extended components are downwardly chamfered at **17**. The flooring plates and flooring beams are thus readily assembled with as close a tolerance between the edges of the downwardly-extended components and the edges of the flanges of the flooring beams as is possible while making accommodation to possible manufacturing variation in the flange dimensions of the flooring beams.

The flooring panel so integrated may be considered complete as a heavy-duty flooring panel for incorporation in a bridge or analogous structure. Such incorporation with underlying stringers **18** is shown in Fig. II and in detail in Fig. VIII of the drawings. As shown, the flooring beams **15** of the flooring panel are integrated with underlying stringers by welding, fillet welds **19** being shown.

If for any reason it is desired to have a closed roadway surface, a suitable continuous plate covering may be superimposed on the open monogenetic flooring plates. Fig. X of the drawings shows a battledeck plate flooring **20** in welded integration with the open plates. As shown, the battledeck flooring **20** is integrated with the underlying open monogenetic flooring plates by a plurality of plug welds **21** made against the horizontal components **2** of the open flooring plates. It should be noted that when a battledeck flooring is added to the primary structure of the monogenetic flooring plate, stress-distributing bars are not required.

Fig. X of the drawings illustrates the fact that the monogenetic trussed flooring plate of my invention is of itself a structural entity, which may be reinforced by the stress-distributing bars, may be covered and reinforced if desired by any suitable covering or may be used without either reinforcement or covering when the dimensions of the plate and the conditions of service render such use practical. Also it is to be understood that the flooring plate in any length in which it is produced from that of a single truss up to a great number of trusses included in the monogenetic plate may be used as an element in a great variety of structures and integrated in them in any manner appropriate to the association in which the flooring plate is used. The primary utility of the flooring plate is in the floor, or deck, of a bridge when integrated with flooring beams into a flooring panel, because such use gives full scope to the advantages of the flooring plate as the primary element of a light weight heavy duty floor suitable for vehicular and other traffic and takes full advantage of the properties of the plate and its associated flooring beams for ease in transportation and installation.

Fig. IX of the drawings shows a plurality of my flooring panels including the monogenetic open flooring plates set to form a roadway, such as the deck of a bridge. As shown in this figure of the drawings, the flooring panels are set with the flooring beams **15** across the direction of traffic and with the downwardly-extended truss components **3** and stress-distributing bars **11** parallel to the direction of traffic. This is a preferred but not a requisite positioning of the flooring panels. As shown, the flooring panels are extended beneath a curbing and/or sidewalk **22** and the flooring plates are so arranged as to stagger the position of the downwardly-extended truss components and the stress-distributing bars in adjacent flooring plates. Such arrangement avoids any possibility of incurring directive travel

and is a desirable though not requisite mounting of the flooring panels.

A preferred method of manufacturing the flooring plate is indicated schematically in Fig. XI of the drawings. As illustrated, the formation of the flooring plate is from a rolled steel sheet and as currently practiced is a two-step operation. Thus, as indicated, the first step consists in punching out the holes 6, 7, 8, 9 and 10. The holes 9 and 10 provide relief for bending the downwardly-extended truss components into their position of angularity with respect to the traffic-contacting surface of the plate in a single step with cutting along the broken-lines 23 shown in this figure of the drawings. Lines 23 indicate how the contour of holes 4 determines the contour of downwardly-extended components 3 and how the contour of holes 6 in the downwardly-extended components 3 is determined by the contour of horizontal traffic-contacting components 2, as the flooring plate is shown in preceding figures of the drawings.

The foregoing makes it clear that my invention in all its aspects is based on sound scientific and engineering principles and that in my invention those principles are adapted to practical requirements of manufacture, transportation and structural assembly and erection. Thus, full advantage is taken of the monogenetic nature of the open flooring plate and its adaptability for integration in a composite flooring panel and bridge super structure. Also the general adaptability of the flooring plate and its inherent ability for stress-distribution has been described and explained. It will be understood that my flooring plate combines the advantages of open metal floors generally considered with advantages peculiar to its own structure. For example, a floor comprising the open flooring plate of my invention has the self-cleaning properties of open floors in general. My floors can advantageously be made of low alloy, high physical, rust-resisting steels. It should be noted further that the floor combines the advantages in transportation and assembly which have been noted above with flexibility in manufacture. That is, the plates can, within reason, be made initially in any predetermined length or variety of lengths which adapts them to installation in particular localities or positions or to particular conditions of use.

Various modification in and to the specific embodiment of my invention as herein illustrated or described may be made without departing from the essence of the invention in which they are

implicit and the scope of my invention is therefore to be limited only by the statement of the claims appended hereto.

I claim as my invention:

- 5 1. An open one-piece rolled metal, heavy-duty, perforated flooring plate having trusses and a horizontal traffic-contacting surface, and having opposed longitudinal margins, spaced transverse openings each of which terminates inwardly adjacent the longitudinal margins of the plate, a continuous downwardly extending substantially straight flange bent from the plane of the traffic-contacting surface along each opening forming spaced trusses on the underside of said plate and transverse openings in said traffic-contacting surface, said horizontal surface having spaced portions extending into said openings in the plane of said traffic-contacting surface.
  - 10 2. A flooring unit comprising the flooring plate set forth in claim 1 and stress distributing bars; said stress bars extending between said downwardly extending flanges forming said trusses and being substantially parallel thereto and being secured to said spaced portions of said horizontal structure of the plate.
  - 15 3. A flooring unit comprising the flooring plate set forth in claim 1 and a compositely acting top plate; said top plate being secured to said horizontal traffic-contacting surface and thus lying on and covering such horizontal traffic-contacting surface.
  - 20 4. A flooring unit comprising the flooring plate set forth in claim 1 and compositely acting flooring beams; said flooring beams being secured to said opposed longitudinal margins of said flooring plate, and extending substantially at right angles to said trusses and being closely adjacent the ends of said trusses.
  - 25 5. A flooring unit as set forth in claim 4 where-40 in supporting beams are mounted below and secured to said flooring beams, said supporting beams extending at right angles to said flooring beams.
